(57) **CLAIM**

The ornamental design for a temperature control device, as
shown and described.

DESCRIPTION

FIG. 1 is a rear perspective view of a temperature control
device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of FIG. 3 thereof.

The dashed broken lines illustrate structure or features
which form no part of the claimed design.

The dot-dash broken lines illustrate an unclaimed boundary.
The dot-dot-dash broken lines identify an area of enlargement.

1 Claim, 8 Drawing Sheets
